UNITED STATES PATENT OFFICE.

EDWARD A. LANGENBACH, OF CANTON, OHIO.

DESIGN FOR A METALLIC SIDING-PLATE.

SPECIFICATION forming part of Design No. 24,486, dated July 16, 1895.

Application filed June 3, 1895. Serial No. 551,574. Term of patent 7 years.

To all whom it may concern:

Be it known that I, EDWARD A. LANGENBACH, a citizen of the United States, and a resident of Canton, county of Stark, State of Ohio, have invented a new and useful Design for a Metallic Wall or Siding Plate, of which the following is a full, clear, and exact description, reference being had to the accompanying drawing, making part of this specification.

My invention relates to a design for a metallic wall or siding-plate.

In the accompanying drawing the figure is an elevation of a wall or siding plate made in accordance with my design.

My design consists of a wall or siding plate divided up into a number of sections and ornamented, as hereinafter described.

In the said drawing, the reference-letter A designates the wall or siding divided, by means of vertical ribs B and alternating circular projections C, into a number of sections D. Each of these sections is divided by means of

curved ribs E into an upper and lower part, and the said upper part is ornamented by a number of raised knobs or studs F. In said lower part there is an ornamental figure G in relief, at each side of which, and also in relief, are leaf-shaped figures H. Above the said figure G is the representation in relief of an Egyptian lamp I, with drapery K at the upper end, and also formed with projections L, representing tongues of flame. In the vacant spaces of the lower section between the ornamental figures there are formed knobs, studs, or circular projections M. The lower section is also provided with horizontal projections N.

What I claim is—

The design for a metallic siding plate herein shown and described.

In testimony whereof I have hereunto set my hand this 17th day of May, A. D. 1895.

EDWARD A. LANGENBACH.
